DESIGN FOR A COMBINED BOTTLE, PEDESTAL, AND COVER THEREFOR

Felix Sang, New York, N. Y., assignor to Parfums Romance, Inc., New York, N. Y., a corporation of New York

Application July 22, 1941, Serial No. 102,370

Term of patent 3½ years

To whom it may concern:

Be it known that I, Felix Sang, a citizen of the United States, residing in the city, county, and State of New York, have invented a new, original, and ornamental design for a Combined Bottle, Pedestal, and Cover Therefor, of which the following is a specification, reference being had to the accompanying drawing, forming a part thereof, in which:

Fig. 1 is a front elevational view of a combined bottle, pedestal and cover therefor, with the transparent cover member removed and showing my new design;

Fig. 2 is a rear elevational view of the same with the transparent cover in place; and

Fig. 3 is a top plan view thereof with the cover in place.

I claim:

The ornamental design for a combined bottle, pedestal, and cover therefor, substantially as shown and described.

FELIX SANG.
